UNITED STATES PATENT OFFICE.

NATHAN A. KURMAN, OF NEW YORK, N. Y., ASSIGNOR TO INTERNATIONAL CALLOPHONE CORPORATION, A CORPORATION OF DELAWARE.

TELEPHONE SYSTEM.

Application filed January 9, 1919. Serial No. 270,835.

The object of my invention is to provide a simple construction of telephone circuits which will be effective in operation and adapted to those systems in which a central 5 station may have articulate communication with a plurality of other stations, such as required in intercommunication on war ships or in callophone systems generally.

My invention is more particularly directed to the system of wiring, whereby the 10 usual induction coils may be dispensed with and incidentally, the elimination of the more or less complicated wiring required with their use in a multiple station installation.

My invention has also a further object, 15 namely, a more effective and efficient transmission of articulate speech than has been possible in systems employing induction coils between the primary or transmitter circuit and the secondary or line circuit in which the receiver is located.

My object is also to provide a system 20 which is flexible in its adaptation to any number of receiving or sub-stations, while maintaining simple circuit wiring.

In my improved system, I employ circuits 25 which connect the battery, not only in series with the transmitter but also in series with the receiver through a condenser; the transmitter and receiver being together in multiple relation with the battery, and associated with an inductance, included in the battery circuit either wholly or partly between the battery and transmitter and effective, by self-induction, in producing variable potential currents, which by means of the condenser, induces alternating currents in the line circuit and receiver therein.

40 In my improved system, the variable resistance of the transmitter (during sound transmission) permits a variable current flow from the battery; and this current being of a pulsatory or undulatory character, produces in the self-induction or impedance coil pulsations of increased electromotive force which, being impressed upon the variable current caused by the action of the transmitter, effectively energizes the condenser and thereby induces alternating currents which pass into the line and energize the receiver. This result may be explained by assuming that the flow of the battery current through the impedance or self-inductance coil is, under the control of

the transmitter, made to surge within the coil and in this manner create variable inducing currents of increased potential difference, which are effective in the condenser to generate secondary currents, to be conveyed by the line circuit to the receiver. 60

The increased potential generated by the self-inductance coil becomes especially effective in the condenser with each increase in resistance of the transmitter and overflows, as it were, into the condenser. This overflow of the current of increased potential may be still further augmented by including in the circuit additional self-inductance effects on either or both sides 65 of the condenser; and in all cases the variable current phase in the receiver circuit will be in timed relation to the varying resistance and current pulsations in the transmitter. 70

Considering the return current from the receiver, it appears to have two paths, one through the transmitter and one through the battery and impedance coil; it cannot flow through the battery and impedance coil, as by the nature of its alternating or pulsatory character, the impedance coil offers an effectual bar; it therefore must flow through the transmitter, which though variable, is non-inductive and acts to short 80 circuit the impedance coil and battery. The ohmic resistance of the transmitter in comparison to the resistance of the receiver circuit is so slight as to be negligible, especially as it is entirely non-inductive, and 85 the variations of the resistance medium have no effect upon the tone of the receiver sounds. 90

My invention consists of method and means whereby the above enumerated results and advantages may be secured, the same being set out hereinafter and more particularly defined in the claims. 95

My invention will be better understood by reference to the drawings, in which: Fig. 100 1 is a diagram illustrating the essential association and combination of parts constituting my improved telephonic apparatus; Fig. 2 is a similar diagram illustrating modification of the same; and Fig. 3 shows 105 a combined circuit embodying the features of Figs. 1 and 2, and with selective means for introducing either into operative condition.

These diagrams are intended to illustrate 110

the essential or characteristic features of embodiment of my invention; and are to be taken as examples of the system in its simplest form and not by way of restriction.

2 is the battery, 6 is the transmitter, and 11 is the receiver. 3 and 4 are the two legs of the battery circuit and these are connected by circuit 5 including the transmitter 6. 10 The conductor 4 includes an impedance or self induction coil 7, whose resistance and coil turns are properly proportioned for the duty to be performed. 8 and 9 are continuations of the battery circuits 3 and 4 respectively, and unite in the receiver 11. Conductor 9, which is an extension of the conductor 4, includes the condenser 10, which prevents direct flow of the continuous current of the battery into the receiver circuit 20 between the condenser and receiver, but receives the overflow current of higher potential and becomes charged to a degree which causes induced discharge through the receiver circuit 9, receiver 11, and conductor 8. 25 In this manner the extra current, so to speak, induced in the self-inductance coil 7 at the moment of change of resistance (increasing) in the transmitter, finds relief in charging the condenser (having predetermined proper 30 capacity) and discharging by induction therethrough into the receiver circuit.

In Fig. 2, the receiver circuit 9 also includes an amount of self-inductance or impedance coils 7^a, which will assist in the 35 building up of potential and insure somewhat more rapid discharges of the condenser. Otherwise, the layout of the system is the same as in Fig. 1, first described.

Referring to the selective system illustrated in Fig. 3, the condenser 10, is shown 40 as in series with the two coil windings 7 and 7^a, of the self-inductance or impedance coil which, as in Fig. 2, are wound upon a common magnetic core. The switch 14 is connected with the line or receiver circuit 9 and is adapted to make connection either with the terminal 12 of the self-inductance or impedance coil 7^a, or with the terminal 13 directly connecting with the condenser 10, as 45 desired, the inclusion of the coil 7^a, being desirable when the system is intended to talk from central or master station to a single distant station (corresponding in operation to Fig. 2), whereas the direct connection of the line 9 with the condenser 10 is more desirable when the central or master station is 50 to talk to a plurality of distant stations (as explained in connection with Fig. 1). In Fig. 3, I have shown the condenser 10 arranged in series with and between the two sections of coil 7 and 7^a of the self-inductance coil, whereas in Fig. 2 I have shown the condenser arranged on the line terminal 55 of the coil winding 7^a, but this difference is 60 immaterial, it sufficing that the condenser

shall be in the circuit between the receiver and self-inductance coil 7, whether the coil 7^a is employed or omitted. Where the system is to be restricted to two stations only, the circuits shown in Fig. 2, will preferably 70 be employed; where more than two stations are to be employed permanently in multiple with the central station, the circuits shown in Fig. 1 will preferably be employed; but when the system is to combine both systems 75 with a selective means, then the circuits shown in Fig. 3 will preferably be employed.

In operation, the current flowing from battery through the transmitter is affected directly by the variable resistance of the 80 transmitter in operation. Obviously, there is a drop of potential across the transmitter terminals, and one terminal of the condenser will be charged to the same potential as the terminal of the transmitter to which it is 85 directly connected (Fig. 1) and the other terminal of the condenser will have a potential commensurate with the other terminal of the transmitter with which it is connected through the line and receiver, allowing for 90 such drop of potential as may result from the interposition of the receiver resistance and that of the line circuit. When the transmitter varies its resistance a variation in voltage across its terminals will occur, and, 95 as a result, a variation across the terminals of the condenser will be effected. This varying of the potential across the terminals of the condenser insures an induced current flow 100 in the line and receiver and hence the production of articulate sounds from the receiver in synchronism with the corresponding potential variations across the terminals of the transmitter. It would appear that the induced current in the line 8, 9, between 105 the condenser 10 and cross circuit 5 from the transmitter 6, and including the receiver 11, is of an alternating character, and in the flow of this alternating current its energy is 110 expended in the self-inductance or impedance coil 7 and 7^a. In this action, the induced alternating current augments the induced or extra-current effects produced in the inductance coils 7 and 7^a and thereby 115 provide a more effective inducing current for charging the condenser 10. In other words, the circuit system may be considered as one in which the undulatory current in the local or transmitter circuit, 3, 4, 5, produced by 120 the action of the variable resistance of the transmitter upon the continuous current flow from the battery 2 is available impressed upon the current in the line 8, 9, through the inductive action of the condenser, coupled with the self-inductive effect which is induced 125 in the impedance coil 7 in the battery circuit and made effective directly (Fig. 1) or through the second coil portion 7^a (Fig. 2) of the impedance coil, and also made effective 130 upon the condenser 10 in producing an 135

increased potential to the induced alternating currents in the line or receiver circuit. The circuits are simple while the reactions produced therein are somewhat complex; but it is believed that the above explanation will suffice to account for the highly effective and efficient results in articulate transmission secured thereby.

Again considering the building up of the E. M. F. by the action of the transmitter upon the battery current flowing through the self-inductance coil, the following explanation may be made:

When the transmitter is reducing its resistance, the self-inductance coil 7 tends to induce a counter electromotive force, which reduces the effective E. M. F. of the battery current, and then when the transmitter increases its resistance, this action quickly reduces the counter E. M. F. and induces an extra E. M. F. and thereby the production of an extra current which charges the condenser, as before explained. It will be understood that the strength of the battery, the ampere windings of the coil 7 and the resistance of the transmitter, all influence the extent of the extra or induced current which is to be effective in producing the secondary current in the receiver circuit.

As before stated, I have shown the simplest form of my invention, but it is to be understood that where there are a plurality of receiver circuits and with their condensers simultaneously operating in parallel from the same battery circuit and transmitter (Fig. 1), the flow of current from battery through the transmitter should increase proportionately to the increase of receiver stations, otherwise the potential energy induced by the condenser would not be strong enough for the most efficient results.

I have now described my invention in a generic sense, but it is to be understood that in actual commercial practice in a multiple unit system, there will be suitable selective switches and other devices, such as signalling means, but these do not form any part of the present invention; and while I have described my invention in the forms found in practice to be best suited to the aims and objects of the invention, I do not restrict myself to the details, as these are susceptible of modification without departing from the spirit of the invention.

Having now described my invention what I claim as new and desire to secure by Letters Patent, is:

1. A telephone system comprising a trans-

mitter; a battery; a self-inductance coil; 60 and a transmitter circuit including the transmitter, battery and inductance coil in series; in combination with a receiver; and a receiver circuit including the receiver, battery and inductance coil and also containing a 65 condenser between the receiver on the one hand and the battery, inductance coil and transmitter on the other hand.

2. The telephonic system defined in claim 1, further provided with an additional self-inductance coil arranged in the receiver circuit in series with the condenser and through which the extra current from the self-inductance coil of the transmitter circuit passes. 75

3. A telephonic system comprising a complete transmitter circuit including a battery, a transmitter, and a self-inductance coil, all arranged in series, combined with a receiver, a condenser, a receiver circuit having one limb connected with one terminal of the battery and the other limb connected with one terminal of the condenser, whereby the receiver is arranged in the receiver circuit between one terminal of the battery and the condenser, and a connection providing an electric circuit between the other terminal of the condenser and the other terminal of the battery through the inductance coil. 80

4. A telephonic system, comprising a source of electric energy, a transmitter, a transmitter circuit including the transmitter in series with the source of energy, a receiver at a distance from the transmitter, a receiver circuit branched from the transmitter circuit so as to form a looped circuit including the receiver and transmitter in series with each other and in multiple relation to the source of electric energy, a condenser in the receiver circuit, and means energized by the source of electric energy and under the control of the transmitter for producing currents of higher electromotive force for energizing the condenser and thereby producing induced currents in the receiver circuit. 95

5. In a telephone system a transmitter circuit, a transmitter and a battery therein, a self-inductance coil also in the transmitter circuit, a receiver circuit, a receiver therein, a condenser in the receiver circuit in series with the receiver, a self-inductance coil in the receiver circuit, and a switch device for putting the last mentioned inductance coil into or out of the receiver circuit. 100

In testimony of which invention, I hereunto set my hand.

NATHAN A. KURMAN.
